RECIPROCAL MOTION DEVICE

Vester O. Pounds, Enid, Okla.

Application March 17, 1941, Serial No. 333,732

3 Claims. (Cl. 74—57)

This invention relates to a reciprocal motion device and is applied to an apparatus for driving oil pumps and has for an object to provide a simplified device for converting rotary movement of a driving unit into rectilinear movement for reciprocating the polish rod of an oil pump.

A further object is to provide a device of this character in which the working tube and housing are provided with interfitting guides which confine the working tube to rectilinear movement.

A further object is to provide a device of this character in which the feed screw is provided with two reversely arranged threads to reverse the direction of the traveling nut and the working tube carried thereby at each limit of stroke, the feed screw being hollow and receiving the polish rod which latter is supported by the working tube so that all of the parts will be accurately centered to promote effective operation of the pump.

A further object is to provide a device of this character which will be formed of a few strong simple and durable parts, which will be inexpensive to manufacture, and which will not easily get out of order.

A still further object is to provide a device of the kind mentioned that is small and compact enough that the entire device and power unit therefor may be placed in a pit over an oil well and a cover may be placed over the pit so as to conceal the device and the location of the well from view as a means of concealing the location of an oil field from the view of an enemy in time of war.

Still a further object is that if the device as above mentioned is used on top of the ground instead of in a pit, a much smaller building will be required to house the power unit and pumps than other devices now in use.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

Now referring to the accompanying drawings;

Fig. 1 is a side elevation of apparatus for driving oil pumps, constructed in accordance with the invention.

Fig. 2 is another side view of the device, the view being taken on an angle of ninety degrees toward the left of that shown in Fig. 1.

Fig. 3 is an enlarged detail plan view of the pumper device.

Fig. 4 is an enlarged detail vertical sectional view through the pumps, the view being taken along the line IV—IV in Fig. 3 and looking in the direction of the arrows.

Fig. 5 is a detail cross sectional view through the pumper device, the view being taken along the line V—V in Fig. 4 and looking in the direction of the arrows.

Fig. 6 is an enlarged side view of the threaded elevation tube.

Fig. 7 is a front view of the tiltable thread element.

Fig. 8 is a rear view of the tiltable thread element.

Fig. 9 is a side view of the tiltable thread element.

Fig. 10 is a top plan view of the tiltable thread element.

Referring now to the drawings in which like characters of reference designate similar parts in the various views, 10 designates a tubular feed screw having two reversely arranged threads 11 and 12. A traveling nut 13 is engaged with the threads and a working tube 14 is threadedly engaged with the traveling nut as shown at 15 to be moved as unit with the nut.

A housing 16 surrounds the working tube and is adapted to be filled with lubricant. As best shown in Fig. 4, the housing is provided with longitudinal guide grooves 17 and the working nut 13 is provided with spaced guide ribs 18 which engage opposite sides of the guide grooves 17 and prevent rotation of the working tube axially within the housing 16.

The upper end of the housing tube 16 is provided with a guide and cap element 19 that is threaded or otherwise suitably attached thereon in such a manner that the tube 14 slidably passes therethrough. The working tube 14 slidably projects through the guide 20 and at the upper end is equipped with a clamp 21 which is secured to the upper end of a polish rod 22. The polish rod 22 extends axially through the tubular feed screw 10 and at the lower end is secured to the pump string, not shown.

The lower end of the housing 16 is seated in a casting 21 and is welded or otherwise suitably and rigidly attached thereto. The casting 21 is provided with an outwardly extending flange portion 21a that is seated on a housing element 22' that is supported on legs 23 that are rigidly attached thereto.

Carried within the housing 22' and also at-

tached thereon is a thrust bearing assembly 24 and a radial bearing assembly 25 on and in which is supported the threaded elevator tube 10.

On the bottom end of the elevator tube 10 is rigidly attached a fly wheel element 26 on which is carried a worm wheel 27 that is bolted thereto and driven by a worm 28 that is carried on a shaft 29 that is rotatably carried in bearings carried within and between the walls of the housing 22' and a closure plate 30 for the bottom side of the housing 22' and which is bolted thereto. In the closure plate 30 is carried a conventional packing gland 31 for reasons that are obvious.

On the upper end of the working tube 14 is a closure nut 32 in the upper end of which is carried the lower part of a thrust bearing 33 and on which rests the upper part of the thrust bearing 33 which is seated in a cap element 34. Around the polished rod 22 and intermediate the cap 34 and the clamp 21 is a helical shock absorption spring 35.

Seated in the threads 11 or 12 is a tiltable thread 36 that is integrally formed on a partial ball element 37 on which is integrally formed a pin 38 that is journalled in a bearing in the nut 13.

Rigidly attached to opposite sides of the nut 13 is one end of a pair of wire ropes 38 and 39 which extend upwardly therefrom and pass through holes 40 and 41 in the cap element 19 and then pass over pulleys 42 and 43 that are rotatably carried on axle pins 44 and 45 that are supported in pairs of ear like elements 46 and 47 that are integrally formed on the cap element 19. Suspended on the other end of the wire ropes 38 and 39 is a pair of counter balance weights 48 and 49 which are housed in tubular elements 50 and 51 at opposite sides of the housing element 16 and supported by clamp elements 52 and 53 that are supported as the housing element 16 and cap element 19 therefor.

In Figures 1 and 2 is shown a power unit 54 which in this case, is an electric motor. The power unit 54' is supported on a concrete base 55. The rotatable motor shaft 56 is connected in driving relationship with the shaft 29 of the pumper device as will be readily understood.

As shown in Figures 1 and 2 the device is positioned in a pit having concrete walls A and which is covered with a cover element B that rests on the top of the walls A approximately at the ground level C.

In the pit is shown a stuffing box 56 and a discharge pipe 57 for the oil well pump, and over which is positioned the pumper device as shown.

The operation of the device is as follows: The power unit is started, whereupon the shaft 29 is revolved, whereupon the worm 38 drives the worm wheel 27 in a rotary motion and which in turn drives the threaded tube 10 in a rotary motion.

The rotary action of the thread 11 is such that the tiltable thread 36 is formed to travel upwardly with the rotating thread 11 and there-

by force the elevator tube 14 to travel upwardly therewith and which in turn also lifts the polish rod 22 and pump rods attached thereto to operate the pump as will be readily understood.

5 Now as the tiltable thread element 36 reaches the top of the thread 11 it will be guided through the thread connection passage D into the thread 12 which will move the tiltable thread and the above mentioned associated parts connected therewith in a downwardly direction until the tiltable thread 36 reaches the bottom of the thread 12 and is guided by the connecting thread passage E back into the thread 11 to repeat the up and down cycle just described for the pumping operation of the well.

Now having fully described my invention, I claim:

1. In a pumper device for wells; a housing element supported on legs, an elevator housing carried on the first said housing, an elevator element, said elevator element being housed within the elevator housing element being movable longitudinally therein and means incident to the elevator housing and the elevator therein for preventing the rotary movement of said elevator element, a rotatable tubular element positioned within said elevator element, said rotatable tubular element being carried in bearings carried by the first said housing element, and means on one end of said rotatable tubular element for rotatably driving said rotatable tubular element, the outside of said rotatable tubular element having right and left hand threads therein that cross each other and merge both into the other at the ends thereof, a tiltable thread element carried by said elevator element and being positioned in said threads so as to elevate and lower said elevator element upon rotation of said rotatable element, a thrust bearing carried on the upper end of said elevator element, and means for supporting a pump actuating rod thereon.

2. In a pumper device for wells as defined in claim 1, and pulley means on the top of said elevator housing, and flexible means passed over and supported by said pulley means, one end of said flexible means being rigidly attached to the lower end of said elevator element, the other end of said flexible means being rigidly attached to weights as a means of counterbalancing the pump load.

3. In a pumper device for wells as defined in claim 1, and pulley means on the top of said elevator housing, and flexible means passed over and supported by said pulley means, one end of said flexible means being rigidly attached to the lower end of said elevator element, the other end of said flexible means being rigidly attached to weights as a means of counterbalancing the pump load, said means for rotating said rotatable element being a worm, and power means for driving said worm.

WESTER O. POUNDS.
